BENJAMIN JACOBY AND HERBERT E. ROUSH, OF MARION, OHIO.

CRAWLING TRACTION MECHANISM.

1,200,438.

Specification of Letters Patent.

Patented Oct. 3, 1916.

Application filed December 20, 1915. Serial No. 67,708.

To all whom it may concern:

Be it known that we, BENJAMIN JACOBY and HERBERT E. ROUSH, citizens of the United States, residing at Marion, in the county of Marion and State of Ohio, have invented certain new and useful Improvements in Crawling Traction Mechanisms, of which the following is a specification, reference being had therein to the accompanying drawings.

This invention relates to crawling traction mechanism, and the object of the invention is to provide a mechanism of this character having a very large degree of flexibility, whereby the sectional track will be enabled to follow closely the contour of the ground or other surface over which the mechanism is moving.

To this end it is a further object of the invention to provide the structure to be transported, along each side, with a plurality of independently movable trucks to engage the endless track and support said structure thereon; and to so construct and arrange these trucks that each will be capable of movement relatively to the structure which is to be transported and to the other trucks; and further to provide each truck with a plurality of track engaging members which will be capable of vertical movement relatively one to the other, as well as relatively to the other trucks.

It is also an object of the invention to provide means for steering a mechanism of this character; to provide means for preventing the cavities of the blocks or sections of the track from filling with mud or the like; and to provide means for lubricating the pivotal connections between the blocks or sections of the track.

It is also an object of the invention to provide a mechanism of this character of a very simple construction and of a strong durable character, whereby the cost of manufacture and of maintenance will be low.

Other objects and advantages of the invention will appear as it is described in detail.

In the accompanying drawings Figure 1 is a side elevation of a mechanism embodying our invention showing same applied to a steam shovel, the upper structure of the shovel being broken away; Fig. 2 is a front end elevation of such a mechanism. Fig. 3 is a plan view partly in section of one of the

trucks; Fig. 4 is a plan view partly in section of the driving and steering mechanism for one of the trucks; Fig. 5 is a side elevation of the mechanism shown in Fig. 4; Fig. 6 is a top plan view of one of the blocks or sections of the track; Fig. 7 is a side elevation of such a block; Fig. 8 is a sectional view taken through the block and tumbler; Fig. 9 is a sectional view taken on the line ⁶⁵ *xx* of Fig. 7, and Fig. 10 is a detail of one of the pivot pins of the track.

In carrying out our invention we provide the main frame of the structure which is to be transported, and which may be an excavating mechanism or any other structure, with a plurality of trucks along each side thereof, these trucks being connected with said frame in such a manner as to permit each truck to have movement in a vertical ⁷⁰ plane relatively to the frame and to the other trucks. These trucks are arranged in engagement with the operative portion of an endless track, which extends about the trucks, and serves to support the structure ⁷⁵ upon the track. Preferably each truck comprises a pivotal frame having on each side of its axis track engaging members, which members are capable of a vertical movement relatively one to the other. Means are also ⁸⁰ provided for imparting driving movement to one of the track engaging members of one truck on each side of the frame, whereby lengthwise traveling movement is imparted to the track and to the structure supported ⁸⁵ thereon. These particular features of the invention may be embodied in mechanisms of various kinds and that here shown has been chosen for the purpose of illustration ⁹⁰ only.

In the accompanying drawings we have illustrated one embodiment of the invention and have shown the same as applied to a steam shovel of the rotary type. This shovel does not comprise any part of the ¹⁰⁰ invention and will be described only to such an extent as is necessary to enable the drawings to be understood.

The steam shovel comprises a main frame ¹ upon which is mounted a revolving platform ¹⁰⁵ 2, and arranged on the main frame 1 concentrically with the axis of the revolving platform is an annular rack 3 with which meshes a pinion 4, carried by the revolving platform and operatively connected with ¹¹⁰ suitable power mechanism which is carried by that platform, whereby the pinion may

be caused to travel about the annular rack and revolving movement imparted to the platform. The main frame 1 is provided near its front and rear ends relatively with 5 axles 5 and 6 which, in the ordinary type of shovel, are provided with traction wheels or railway wheels to enable the shovel as a whole to be transported from one point to another and to be advanced as the excavation 10 progresses. In applying our invention to this revolving shovel we have utilized the front and rear axles 5 and 6 in substantially their usual form, making only such detail changes in the construction as are necessary 15 to accommodate them to the present mechanism.

To apply the crawling traction mechanism to the main frame of a structure of this kind we have provided a plurality of trucks 20 which are movably connected with the main frame 1 and are provided with track engaging members to engage the endless track, which is indicated as a whole by the reference numeral 7, and support the structure 25 thereon. Preferably there are two of these trucks upon each side of the main frame, and in the present instance, we have pivotally connected the trucks with the main frame so that each truck is capable of movement 30 in a vertical plane about its axis, thereby enabling its track engaging members to rise and fall relatively to each other and relatively to the other trucks. The track 7 comprises a series of sections or blocks 8, 35 each of which comprises a tread portion consisting of a block of wood 9 covered with sheet metal 10, to protect the same from wear. Secured to the inner face of each of the blocks is a link or casting 11, having at 40 one side a lug 12 and having at its other side ears 13 adapted to receive the lug 12 of an adjacent section of the track. Pivot pins 14 extend through the ears and lugs to pivotally connect the links and their sections one 45 to the other, on axes extending transversely to the length of the track. If desired, each connecting pin 14 may be provided with an oil conduit 15 opening at its inner end into the bearing of the lug 12 and having at its 50 outer end an enlarged chamber 16, adapted to receive grease and to be closed by a plug 17. We also prefer to counter-sink the outer surface of the wood block 9 and its protecting plate 10 to receive the heads of the bolts 55 18, by means of which the block is connected with the link or casting 11. Each link is provided with central cavity 19 to receive the tooth of an actuating member, as will be hereinafter described. In the particular 60 construction here shown each truck comprises a frame member 20, pivotally mounted between its ends upon the main frame and preferably journaled on the end portion of one of the axles, 5 and 6. Each frame member is bifurcated to receive between its

ends on opposite sides of its axis, track engaging members.

Journaled between the two parts of each frame member, at that end adjacent to the end of the main frame, is a tumbler 21 having about its periphery a series of projections or teeth 22 adapted to enter the cavities 19 in the blocks or sections of the track. These tumblers constitute guides about which the endless track extends and they also serve to support the ends of the respective truck frames. Further, as will hereinafter appear, the tumblers of the trucks at one end of the frame comprise driving members by means of which the traveling movement is imparted to the track. These tumblers may be of various shapes, but we prefer that here shown, in which they have a hexagonal shape, each edge being substantially equal in length to the width of one of the track sections or blocks, and each edge being provided with a tooth 22. Preferably each tooth 22 is tapered as shown and the front and rear walls of the cavities 19 in the track sections converge away from the 90 tumbler, thus providing an enlarged opening to receive the end of the tooth and facilitating the entrance of the tooth into the cavity. At the same time the inner end of the tooth fits comparatively closely in the 95 adjacent end of the cavity and there is no unnecessary play between these parts. These mechanisms are frequently employed where there is a great deal of mud or loose dirt, quantities of which will enter the cavities in 100 the track, and, unless some means is provided for removing the same, will be packed in the cavities by the teeth of the tumblers and the cavities gradually filled. To remove this mud or dirt from the cavities we 105 have formed each tooth of the tumblers hollow and open at both ends, as shown on 23, and have tapered the opening outwardly, consequently, any loose dirt or mud in the cavity will be forced up through the opening in the tooth into the hollow interior of the tumbler, which is provided with openings 24, through which it may escape. The track engaging member at the opposite or inner end of each truck frame preferably 110 comprises a supplemental frame 25, pivotally mounted between its ends on the truck frame and having journaled therein a plurality of rollers 26 adapted to engage the track and travel over the same, it being 115 noted that the inner surfaces of the links 11 form a continuous track over which these rollers can move. In the present instance we have provided each supplemental frame 25 with four (4) rollers and have made 120 the frames of such length that there is a comparatively short space between the inner ends of the track engaging members of the front and rear trucks. Consequently, the 125 load is distributed over practically the en- 130

tire operative portion of the track. Because of the construction of the trucks it will be obvious that the track will follow very closely any irregularities in the surface of the ground over which it is traveling, thus enabling substantially the entire operative length of the track to remain constantly in engagement with the ground regardless of the contour thereof. For example, if the forward portion of one track should engage a stone the tumbler of the forward truck will rise to permit the blocks or sections of the track to position themselves along the sides and top of the stone, this being accomplished without lifting the adjacent blocks or sections of the track out of engagement with the ground. As the track advances and the forward tumbler moves past the stone it will descend to its normal position and the forward end of the inner track engaging member will be lifted to follow the track over the stone, the rear end of the truck frame moving upward to permit this track engaging member to pass over the stone. Thus it will be apparent that the track will follow very closely any irregularities, either elevations or depressions, in the ground over which it is traveling and that the elevation or depression of one portion of the track will not result in the lifting of another portion of the track out of engagement with the ground, as results where rigid truck frames are employed. The track is carried upward over the trucks and suitable guide rollers 27 are provided to support the same out of engagement with the trucks; preferably these rollers are mounted on brackets carried by the truck frames and extending upwardly therefrom. The power mechanism of the shovel is preferably employed to impart traveling movement to the track and the power is, in the present instance, applied to the track through one of the tumblers. To this end the tumbler at the rear end of the machine, on each side thereof, is provided with a sprocket wheel 28 which in the present construction is mounted on the axle 29 of the tumbler, which is journaled in the side members of the truck frame 20 and projects beyond the inner side of this truck frame, as shown in Fig. 3. The sprocket wheel 28 is connected by means of a sprocket chain 30, with a sprocket wheel 31 rigidly secured to the rear axle 6 which is journaled on the main frame and may be driven from the power mechanism of the shovel in any suitable manner. In the present instance we utilize a driving mechanism similar to that commonly employed for propelling shovels of this type. This driving mechanism consists of a bevel gear 32 rigidly secured to the axle 6 and meshing with a bevel pinion 33 on a shaft 34, arranged beneath the main frame 1 and connected by bevel gearing 35

and 36 with a shaft 37 arranged at the axis of rotation of the platform 2 and connected at its upper end by suitable gearing with the power mechanism of the shovel. Thus the motor on the revolving platform drives the axle 6 and the power is transmitted through the sprocket chain 30 to the rear tumblers, and these tumblers are caused to travel along the links 11 of the track and to advance the main frame 1. This of course also advances the forward trucks and the tumblers of these trucks also traveling in the links of the track, to carry the upper or idle stretch of the track forward and place succeeding sections of the track in their proper positions beneath the track engaging members.

While mechanisms of this character do not require a great deal of steering it is desirable that some means should be provided by which they can be turned, or the direction of movement can be altered. In the present construction we accomplish this by providing means by interrupting the movement of one track while the other track continues to advance. To this end we have loosely mounted the driving sprocket wheels 28 on the axles of the driven tumblers, and have provided suitable clutch mechanisms for connecting the sprocket wheels with the axles. As here shown a clutch member 38 is splined upon each axle and cooperates with the clutch member 39, rigidly secured to and preferably formed integrally with the sprocket wheel. The clutch member 38 is actuated by means of a yoke 40 which is pivotally mounted upon a bracket 41 extending laterally from supporting frame or plate 42, which is mounted at its ends upon the axle 29 and the axle 6, respectively. The yoke may be actuated to shift the clutches in any suitable manner, but in the present arrangement, where it is desirable to shift the clutches at infrequent intervals only, we have provided operating levers 43, extending to the rear of machine and arranged to be grasped by the operator when standing on the ground in the rear of the machine. To retain the clutches either in their operative or inoperative positions, each yoke is provided with a finger 44 extending through an opening 45 in the plate 42 and having an aperture adapted to be moved into alignment with one of two apertures formed in a lip 46 projecting from the plate 42 and to receive a pin which serves to hold the finger 44 and, consequently, the clutch in their adjusted positions.

The operation of mechanism will be readily understood from the foregoing description and it will be apparent that the construction and arrangement of the several parts are such that a very large degree of flexibility is secured and the track is enabled to shape itself to fit closely into or about irregularities in the ground over

which it is traveling, this being permitted by the movability of the trucks. Further it will be apparent that this construction is such as to enable us to provide a 3-point support for the main frame of the structure to which the invention is applied, thereby enabling this main frame to remain in a substantially horizontal position when the trucks rise or fall as they travel over the ground, and relieving this main frame of much of the strain which would otherwise be imposed thereon. This 3-point support is secured by pivotally mounting the forward end of the frame upon the forward axle 5, as shown in Fig. 2. In this connection it may be noted that either end of the machine may constitute the front end, as the mechanism moves in either direction with equal ease. It will also be noted that the construction of the front and rear trucks is substantially the same. The only material difference is that one of the trucks on each side, preferably the front truck, has its tumbler adjustably mounted therein to enable the tension of the endless track to be adjusted. This adjustability of the tumbler is secured by mounting its axle 29 in slide blocks 47, which in turn are mounted in guideways or slots 48 formed in the outer ends of the two parts of the truck frame. Set-screws 49 extend into a slot or guideway and engage the slide blocks to hold them in their adjusted positions. Further it will be apparent that the mechanism is simple in its construction and is of a very strong durable character, thus enabling it to be manufactured and maintained at a low cost.

While we have shown one embodiment of our invention we wish it to be understood that we do not desire to be limited to the details of construction shown and described, for obvious modifications will occur to a person skilled in the art.

Having now fully described our invention what we claim as new and wish to secure by Letters-Patent is:

1. The combination with a frame and an endless track arranged lengthwise thereof, of a plurality of trucks connected with said frame at separated points to support the same upon said track, each of said trucks having a rotatable member supported in engagement with said track and capable of vertical movement relatively to said frame and to the other of said trucks.

2. The combination with a frame and an endless track arranged lengthwise thereof and comprising a series of open links, of a plurality of trucks connected with said frame at separated points to support the same on said track, each of said trucks having a rotatable member provided with teeth to enter the links of said track, and each of said rotatable members being capable of

vertical movement relatively to said frame and to the other of said trucks.

3. The combination with a frame and an endless track arranged lengthwise thereof and comprising a series of open links, of a plurality of trucks connected with said frame at separated points to support the same on said track, each of said trucks having a rotatable member provided with teeth to enter the links of said track, and each of said rotatable members being capable of vertical movement relatively to said frame and to the other of said trucks, and means to rotate one of said rotatable members to impart traveling movement to said track.

4. The combination with a main frame and an endless track arranged lengthwise thereof, of truck frames pivotally mounted at separated points on said frame and having rotatable members engaging said track, and means to cause longitudinal traveling movement to be imparted to said track.

5. The combination with a frame and an endless track arranged lengthwise thereof and comprising open links, of a plurality of trucks connected with said frame at separated points to support the same on said track, each of said trucks comprising a pivotal frame member, and a tumbler journaled in each of said frame members and having teeth to enter the open links of said track.

6. The combination with a main frame and an endless track arranged lengthwise thereof, of a plurality of trucks connected with said frame at separated points to support the same on said track, each of said trucks comprising a frame pivotally supported between its ends, and track engaging members connected with the respective ends of each of said truck frames to support said trucks on said track.

7. In a mechanism of the character described a main frame trucks secured to said frame near the respective ends thereof, each truck comprising a pivoted frame having its free end extending toward the adjacent end of said main frame, and a tumbler journaled on said free end of each of said truck frames, and an endless track extending about said trucks and said tumblers.

8. In a mechanism of the character described a main frame, trucks secured to said main frame near the respective ends thereof, each truck comprising a pivoted frame having its free end extending toward the adjacent end of said main frame, and a rotatable toothed member journaled on said free end of each of said truck frames, and an endless track extending about said trucks and said rotatable members.

9. In a mechanism of the character described a main frame, trucks secured to said

main frame near the respective ends thereof, each truck comprising a pivoted frame having its free end extending toward the adjacent end of said main frame, and a rotatable toothed member journaled on said free end of each of said truck frames, and an endless track extending about said trucks and said rotatable members and having open links to receive the teeth of said rotatable members, and means for rotating one of said toothed members to impart traveling movement to said track.

10. In a mechanism of the character described the main frame, trucks secured to said frame near the respective ends thereof, each truck comprising a pivoted frame having its free end extending toward the adjacent end of said main frame, and a rotatable member journaled on the free end 20 of each of said truck frames and having a plurality of straight edges of substantially equal length, each of said edges being provided with a tooth, and an endless track extending about said trucks and said rotatable members and comprising a series of open links to receive the teeth on said rotatable members.

11. In a mechanism of the character described a frame, an endless track extending 30 along each side of said frame, an axle pivotally mounted between its ends near one end of said frame, a truck mounted on each end of said axle, track engaging members carried by said trucks to support the latter on 35 said tracks, other trucks arranged on the respective sides of said frame near that end thereof opposite said axle, and having track engaging members to support the same on said tracks and means to cause traveling 40 movement to be imparted to said tracks.

12. In a mechanism of the character described a frame, an endless track extending along each side of said frame, an axle pivotally mounted between its ends near one end 45 of said frame, trucks mounted on the respective ends of said axle and having track engaging members to support the same on said tracks, a second axle mounted on said frame near that end thereof opposite said 50 pivoted axle, trucks mounted on the respective ends of said second axle and having track engaging members to support the same on said tracks, means for rotating said second axle and a driving connection between 55 said second axle and a track engaging member of each of the trucks carried thereby.

13. In a mechanism of the character described, a frame, an endless track extending along each side of said frame, an axle pivotally mounted between its ends near one end 60 of said frame, trucks mounted on the respective ends of said axle and comprising pivoted truck frames and tumblers carried thereby to engage the respective tracks, other trucks 65 arranged on the respective sides of said

frame near that end thereof opposite said axle and comprising pivoted truck frames and tumblers to engage the respective tracks, and means to cause traveling movement to be imparted to said tracks.

14. The combination with a main frame, and an endless track arranged lengthwise thereof, of a truck connected with said main frame and comprising a frame member pivoted between its ends on an axis transverse to said track, a tumbler journaled in a normally fixed bearing at one end of said frame member and forming a guide about which said track extends, and a track engaging roller mounted at the other end of 75 said frame member for bodily movement relatively thereto and coöperating with said tumbler to support said truck on said track.

15. The combination with a main frame and an endless track arranged lengthwise 80 thereof, of a truck connected with said main frame and comprising a frame member pivoted between its ends on an axis transverse to said track, a tumbler journaled in a normally fixed bearing at one end of said 85 frame member and forming a guide about which said track extends, a supplemental frame pivotally connected with the other end of said frame member, and a plurality of track engaging members carried by said supplemental frame.

16. A truck for a crawling traction mechanism, comprising a frame having a bearing extending transversely thereof between its ends, and arranged to divide the same into 100 unequal portions, a tumbler rotatably mounted in a normally fixed bearing near the outer end of the longer portion of said frame, and a track engaging device carried by the shorter portion of said frame.

17. A truck for crawling traction mechanism comprising a frame having a bearing extending transversely thereof between its ends, a tumbler rotatably mounted in a normally fixed bearing near one end of said 110 frame and a track engaging device secured to the other end of said frame, and comprising a supplemental frame pivotally mounted on said frame at that end opposite said tumbler, and a plurality of track engaging rollers carried by said supplemental frame.

18. A truck for crawling traction mechanism comprising a frame having a bearing extending transversely thereof between its ends, a tumbler rotatably mounted at one 120 end of said frame and a track engaging device secured to the other end of said frame and comprising a supplemental frame pivotally mounted on said frame at that end opposite said tumbler, and a plurality of track engaging rollers carried by said supplemental frame.

19. The combination with a main frame, an endless track arranged lengthwise thereof,

- of an axle carried by said main frame and projecting beyond the sides thereof, a truck frame pivotally mounted on each end of said axle, a track engaging member mounted 5 in normally fixed bearings on each of said truck frames on one side of said axle, and another track engaging member mounted on each truck frame on the other side of said axle and capable of bodily movement relatively to said truck frame.
- 10 20. The combination with a main frame, and an endless track arranged lengthwise thereof, of an axle carried by said main frame near each end thereof, the ends of each 15 axle projecting beyond the respective sides of said main frame, a truck frame pivotally mounted on each end of each of said axles and a track engaging member secured to each end of each of said truck frames.
- 20 21. The combination with a main frame, and an endless track arranged lengthwise thereof, of an axle carried by said main frame near each end thereof, the ends of each 25 axle projecting beyond the respective sides of said main frame, a truck frame pivotally mounted on each end of each of said axles, a tumbler journaled on the outer end of each of said truck frames, and a supplemental frame pivotally mounted on the inner end of 30 each of said truck frames, and track engaging rollers carried by each of said supplemental frames.
22. The combination with a main frame, and an endless track arranged lengthwise 35 thereof, of truck frames pivotally mounted on said main frame near the respective ends thereof, a tumbler journaled on the outer end of each of said truck frames, one of said tumblers being adjustable lengthwise of said 40 track, and track engaging members carried by the inner ends of said truck frames.
23. The combination with a main frame and an endless track arranged lengthwise of said frame on each side thereof, of trucks 45 connected with said main frame on the respective sides thereof, each of said trucks having track engaging members to support the same upon said track, and means for separately actuating said trucks, whereby 50 turning movement may be imparted to the mechanism as a whole.
24. The combination with a main frame and an endless track arranged lengthwise of said frame on each side thereof, of a plurality of trucks arranged on each side of said frame, said trucks having tumblers to engage the respective tracks, power mechanism carried by said main frame, an operative connection between said power mechanism and one of the tumblers on each side of said frame, to cause traveling movement to be imparted to the respective tracks, and means for independently controlling the operative connection between said power 60 mechanism and the respective tumblers.
- 65 25. The combination of a main frame, an endless track arranged lengthwise thereof, and an axle carried by said frame, of a truck frame mounted on said axle, a tumbler axle journaled in said truck frame, a tumbler 70 mounted on said tumbler axle, a driving member mounted on said tumbler axle and capable of rotation independently of said tumbler, clutch mechanism to connect said driving member with said tumbler, a bracket 75 supported at its respective ends on said axles, a yoke pivotally mounted on said bracket and operatively connected with said clutch mechanism, means for actuating said yoke, and means for imparting operative 80 movement to said driving member.
26. The combination of a main frame, an endless track arranged lengthwise thereof, and an axle carried by said frame, of a truck frame mounted on said axle, a tumbler axle 85 journaled in said truck frame, a tumbler mounted on said tumbler axle, a driving member mounted on said tumbler axle and capable of rotation independently of said tumbler, clutch mechanism to connect said 90 driving member with said tumbler, a bracket supported at its respective ends on said axles, a yoke pivotally mounted on said bracket and operatively connected with said clutch mechanism, means for actuating said yoke, 95 means for securing said yoke in adjusted positions, and means for imparting rotative movement to said driving member.
27. In a mechanism of the character described the combination with a track comprising a series of sections, each section having an opening in the inner portion thereof, said opening being closed at its outer end, of a truck having a track engaging member provided with a plurality of teeth, adapted 100 to enter the openings in said track sections, each of said teeth being hollow and being 105 open at both ends.
28. In a mechanism of the character described the combination with a track comprising a series of sections, each section having an opening in the inner portion thereof, said opening being closed at its outer end, of a truck comprising hollow tumbler having a plurality of hollow teeth adapted to 110 enter the openings in said track sections, each of said teeth having an opening in its outer end to permit foreign matter in the 115 openings in said track sections to be forced through the same into the hollow tumbler.
29. In a mechanism of the character described, the combination with a track comprising a plurality of sections, each section having a cavity in the inner side thereof, the front and rear walls of said cavities converging toward the outer side of said section, of a truck comprising a tumbler having a plurality of teeth to enter the cavities 120 of said track section, said teeth having their front and rear faces converging outwardly. 130

30. The combination with a main frame, and an endless track arranged lengthwise thereof, of a plurality of trucks connected with said frame at separated points to support the same upon said track, said trucks comprising frame members pivotally supported between their ends, track engaging members mounted in normally fixed bearings on the outer ends of the respective frame members and forming guides for the track, and other track engaging members mounted at the inner ends of the respective frame members for bodily movement relatively thereto and coöperating with the first mentioned track engaging members to support said truck upon the track.

31. The combination with a main frame, and an endless track arranged lengthwise thereof, of a plurality of trucks connected with said frame at separated points to support the same upon said track, said trucks comprising frame members pivotally supported between their ends, track engaging members mounted in normally fixed bearings on the outer ends of the respective frame members and forming guides for the track, and other track engaging members mounted at the inner ends of the respective frame members for bodily movement relatively thereto and coöperating with the first mentioned track engaging members to support said truck upon the track, one of said frame members being mounted for bodily vertical movement relatively of the said main frame.

32. The combination with a main frame and an endless track arranged lengthwise thereof, of a plurality of trucks connected with said frame at separated points to support the same on said track, said trucks comprising frame members pivotally supported between their ends, track engaging members mounted in normally fixed bearings on the outer ends of the respective frame members and forming guides for said track, supplemental frames pivotally mounted at the inner ends of the respective frame members, and a plurality of track engaging rollers carried by each of said supplemental frames.

33. The combination with a frame and an endless track arranged lengthwise thereof, of a plurality of trucks connected with said frame at separated points to support the same upon said track, each of said trucks having a rotatable member supported in engagement with said track, and one of said trucks being capable of bodily vertical movement relatively to said frame.

34. The combination with a main frame and an endless track arranged lengthwise thereof, of truck frames pivotally mounted at separated points on said main frame and having rotatable members engaging said track, one of said truck frames being capable of bodily vertical movement relatively to said main frame.

In testimony whereof, we affix our signatures hereto.

BENJAMIN JACOBY.
HERBERT E. ROUSH.
